BUILDER MECHANISM FOR SPINNING FRAMES

Walter J. Jacques, Blackstone, Mass., assignor to
Whitin Machine Works, Whitinsville, Mass., a
corporation of Massachusetts

Application February 24, 1937, Serial No. 127,499

5 Claims. (Cl. 242—43.3)

This invention relates to the builder mechanism of a spinning or twisting frame, and relates more particularly to mechanism for winding a preliminary bunch of yarn or thread on the barrel of a weft bobbin in such a machine.

Such preliminary bunches of yarn are useful on weft bobbins which are used in automatic looms, where the replacement of substantially exhausted bobbins is controlled by the coaction of a detecting element or feeler with the weft on the bobbin. The provision of a substantial initial bunch of weft yarn on the barrel of the bobbin causes an abrupt change in diameter to take place when the bunch is wound off, and at which time an indication of transfer is desired. By reason of this marked change in diameter, the indication for a bobbin change is much more reliably given.

It is the general object of my invention to provide improved and simplified mechanism by which 20 a bunch of predetermined size may be wound on a bobbin and by which a shift to the regular wind will then automatically take place.

A further object of my invention is to provide 25 convenient and effective means by which the size of the bunch may be varied as desired.

My invention further relates to arrangements and combinations of parts which will be herein-after described and more particularly pointed out in the appended claims.

30 A preferred form of the invention is shown in the drawings, in which

Fig. 1 is a partial side elevation of a spinning frame embodying my improvements;

Fig. 2 is a sectional end elevation, taken substantially along the line 2—2 in Fig. 1;

Fig. 3 is a partial sectional side elevation, taken substantially along the line 3—3 in Fig. 2;

Fig. 4 is a detail elevation, looking in the direction of the arrow 4 in Fig. 3; and

Fig. 5 is a view of a bobbin with a bunch wound thereon.

Referring to the drawings, I have shown portions of a spinning frame including an end frame member 10 (Fig. 1), a fixed ring rail 11 and a plurality of spindles 12 mounted on a vertically movable spindle rail 14.

The spindle rails 14 at the opposite sides of the spinning frame are slideable on vertical guide rods 16 and are secured to cross members or supports 18 (Fig. 2) connected by hooks 19 and belts 20 to pulleys 21 and 22, the belts being secured to the peripheries of the pulleys and being adapted to be wound thereon. The pulleys are rotatable about fixed axes.

55 A chain 24 has one end thereof secured by a

screw 25^a to the pulley 21 and the chain is wrapped partially around the pulley. From the top of the pulley 21 the chain 24 extends cross-wise of the machine and under and around the pulley 22, as indicated in Fig. 2. The end of the 5 chain 24 is then brought downward over and around a third pulley 25, to which it is secured at 26. The chain 24 may also be secured to the pulley 22 by a screw 27.

A second chain 30 has its upper end passed 10 around a slightly larger portion of the pulley 25 and is secured thereto by a screw 32. At its lower end the chain 30 passes partially around a pulley 33, to which it is secured by a screw 34. The pulley 33 is mounted on a stud or cross shaft 35 15 in a builder lever 36 which swings about a fixed pivot 37 supported by the frame 10. The pulley 33 is provided with a worm wheel 38 engaged by a worm 39 rotatably mounted on a shaft 39^a in the builder lever 36, which shaft has a pick wheel 20 40 at its outer end.

A pick lever 41 (Fig. 1) is loosely mounted to 25 swing about the axis of the worm wheel shaft 39^a and pick wheel 40, and the lever 41 is provided with a pawl 42 engaging the ratchet wheel 43. 30 As the builder lever moves upward, the lever 41 and pawl 42 swing downward on their idle return stroke, and as the builder lever thereafter moves downward, the lever 41 is engaged by a stop pin 43 and accordingly swings in a clockwise direction to advance the ratchet wheel 40 and worm wheel 39 and thus gradually lower the cross members 18, spindle rails 14 and spindles 12 relatively 35 to the fixed ring rails 11.

For a more complete description of this mechanism for gradually lowering the spindle rails, reference is made to the prior patent to Kooistra No. 1,926,390, issued September 12, 1936.

My present invention relates to improved devices for varying and controlling the traverse or 40 swing of the builder lever 36, thus causing a bunch to be wound on the bobbins B supported by the spindles 12. The approximate size and desired location of the bunch is indicated at A in Fig. 5, with the dotted lines a indicating the size 45 and shape of the fully wound bobbin.

A regular builder cam 44 (Fig. 3) is keyed to a cam shaft 45 rotatable in a bearing 45^a on the end frame member 10, and said cam engages an elongated cam roll 47 rotatably mounted in the 50 upper part of the builder lever 36.

The cam shaft 45 may be provided with a gear 48 (Fig. 1) forming part of a driving gear train of the type common in spinning and twisting machines, and through which gear train the 55

shaft 45 and cam 44 are continuously rotated at a uniform speed.

A second or auxiliary cam 50 (Fig. 3) is loose on the cam shaft 45 but is held from axial movement thereon by a locking ring 51. A series of clutch teeth 52 are formed on the end of the hub 53 of the cam 50, and a similar series of clutch teeth 54 are formed on the adjacent end of a clutch collar 55 which is keyed to the cam shaft 45 but is free to slide on said shaft, except as outward sliding movement is limited by a collar 56.

The clutch collar 55 is grooved to receive pins in the forked lower ends of a yoke arm 60 mounted 15 on a rock shaft 61 (Fig. 2) supported in a bearing bracket 62. An arm 63 (Fig. 3) is secured to the rock shaft 61 and extends horizontally therefrom. A handle 66 (Fig. 1) is also secured to the rock shaft 61 and constitutes means by which the 20 clutch teeth 52 and 54 may be engaged. A spring 67 normally draws the arm 63 downward and tends to separate the clutch teeth.

A latch 70 (Figs. 2 and 4) is pivoted at 71 on the bracket 62 and has a hook-shaped lower end 25 adapted to underlie and support the arm 63 and to hold the clutch teeth in engagement. A cord or chain 74 (Fig. 2) extends down through a hole 75 (Fig. 3) in an upward extension 76 of the latch 70 and also extends around a guide pulley 77 mounted on the bracket 62. The lower end of 30 the cord 74 extends through a hole 78 in the web of the cam 50, near the hub 53, and may be secured to the opposite face of the web as by a screw 79.

The upper end of the cord 74 extends around 35 a second guide pulley 80 and is provided with a weight W. A sleeve or bushing 81 may be secured to the cord 74 at any desired point by a clamping screw 82.

Having described the details of construction 40 of my improved bunch building mechanism, I will now describe the operation thereof.

When the time comes for doffing, the operator 45 will stop the frame with the builder lever 36 substantially in its lowest position, with the cam roll 47 engaging the regular cam 44 substantially at its toe or point of greatest radius, as indicated in Fig. 2. The operator will then wind up the spindle rails by applying a wrench to the worm shaft 39^a (Fig. 2) and rotating the pulley 33 in 50 an anti-clockwise direction. The operator then swings the lever 66 (Fig. 1) to the left, thus moving the clutch collar 55 to the right and causing the clutch teeth to become engaged. At the same 55 time, the arm 63 is swung upward and is caught by the latch 70, as indicated in Fig. 4.

When the machine is then placed in operation, 60 the cams 44 and 50 will rotate together and substantially in the relation shown in Fig. 2. As the cam roll 47 underlies both cams, the lever will be positioned by whichever cam is of greatest radius at a given point, and consequently there will be two short traverses of the builder lever 36 and spindle rail 14 for each revolution of the cam shaft, instead of the usual single long traverse, 65 and this operation will continue as long as the arm 63 is held upward by the latch 70.

Rotation of the cam 50, however, causes the cord 74 to be wound around the hub 53 of the cam 50, thus drawing the sleeve or bushing 81 progressively toward the upward extension 76 of the latch 70.

When the bushing engages the part 76, the latch is withdrawn, the lever 63 is released and 75 the clutch collar 55 moved to the left releasing

the cam 50. The bushing should be so located on the cord or chain 74 that the latch will be withdrawn when the cam 44 is engaged by the cam roll 47. The weight W then returns the cam 50 to the initial position indicated in Figure 5 3, with its shortest radius or heel at the bottom, in which position it will not be at any time engaged by the cam roll 47 during the regular wind, as the heel of the regular cam is of greater radius than the heel of the auxiliary cam. The winding of the bobbin thereafter proceeds under the control of the regular cam 44 in the usual way.

By adjusting the position of the sleeve 81 on the cord 74, the size of the bunch A on the bobbin B may be increased or decreased as desired. 15

It will thus appear that I have provided an extremely simple mechanism for winding a bunch of any desired size on a weft bobbin, and for automatically restoring regular traverse when the desired bunch is attained. 20

While I have described my invention as applied to a spinning frame having a movable spindle rail, it will be understood that the invention is equally adaptable to spinning frames having a movable ring rail, and to spinning 25 frames having both a movable spindle rail and a movable ring rail.

Having thus described my invention and the advantages thereof, I do not wish to be limited to the details herein disclosed, otherwise than as 30 set forth in the claims, but what I claim is:

1. In a builder motion, a builder lever and roll, a regular builder cam fixed to a continuously rotated shaft, an auxiliary cam normally loose on said shaft, means to connect said auxiliary 35 cam to rotate with said regular cam to wind a bunch, means to disconnect said auxiliary cam, and separate means additional to said shaft effective to rotate said auxiliary cam to a predetermined initial angular position when released 40 and to hold said cam in said position and out of contact with said builder lever and roll.

2. In a builder motion, a regular builder cam fixed to a continuously rotated shaft, an auxiliary cam normally loose on said shaft but rotatable in a fixed plane, a builder lever and roll coacting with said cams, means to connect said auxiliary cam to rotate with said regular cam to wind a bunch, means to disconnect said auxiliary cam, and separate means additional to said 45 shaft effective to return said auxiliary cam to a predetermined initial angular position when released, in which position the toe of said auxiliary cam is remote from said lever and roll, and to hold said cam in said position. 50

3. In a builder motion, a regular builder cam, means to continuously rotate said cam, a normally stationary auxiliary cam, both of said cams rotating in fixed planes, manual means to connect said auxiliary cam to rotate with said regular cam to wind a bunch, a builder lever having a portion normally engaged by said regular cam but alternately engageable by both cams when said cams are rotated together, and automatic means to disconnect and stop said auxiliary cam 60 when a bunch of predetermined size has been wound, and said latter means comprising a member manually adjustable to determine the size of the bunch. 65

4. In a builder motion, a regular builder cam 70 fixed to a continuously rotated shaft, an auxiliary cam normally loose on said shaft, means to connect said auxiliary cam to rotate with said regular cam to wind a bunch, a flexible member connected to said auxiliary cam and wind- 75

able on the hub of said auxiliary cam when said cam is rotated, an abutment on said flexible member, and a release device for said auxiliary cam engageable by said abutment.

5. In a builder motion, a regular builder cam fixed to a continuously rotated shaft, an auxiliary cam normally loose on said shaft, means to connect said auxiliary cam to rotate with said regular cam to wind a bunch, a flexible member

connected to said auxiliary cam and windable on the hub of said auxiliary cam when said cam is rotated, an abutment on said flexible member, a release device for said auxiliary cam engageable by said abutment, and a weight on said flexible member effective to return said member and auxiliary cam to initial position when released by said device. 5

WALTER J. JACQUES.
